UNITED STATES PATENT OFFICE.

JOEL REN, OF PARROTTSVILLE, TENNESSEE.

CAR-COUPING.

SPECIFICATION forming part of Letters Patent No. 248,503, dated October 18, 1881.

Application filed August 19, 1881. (Model.)

To all whom it may concern:

Be it known that I, JOEL REN, of Parrottsville, in the county of Cocke and State of Tennessee, have invented a new and Improved Car-Coupler, of which the following is a full, clear, and exact specification.

The invention consists of a horizontal pincher-like pair of clamps pivoted above the draw-head of a car on a suitable support, with the long legs of the clamp extending forward and carrying a sliding ring, and the jaws or short legs directly above the coupling-pin aperture in the draw-head in position for grasping the coupling-pin; and, further, of a horn or a rod bent at right angles, fixed in and projecting from the end of an opposite car, whereby, when the cars approach each other, the clamp may be opened to release the coupling-pin, that the latter may drop into the draw-head and hold the coupling-link.

Figure 1 is a plan of my improved device applied to cars. Fig. 2 is a sectional side elevation of the same.

Similar letters of reference indicate corresponding parts.

In the drawings, A A' represent two opposite cars, having draw-heads B B'.

Projecting from the front of car A, immediately over the draw-head B and parallel therewith, is a rectangular frame, C, on the front and center of which, on a vertical pivot, a, is pivoted the pincher-like clamp D, whose jaws b are directly above the vertical coupling-pin hole c in the draw-head B, and whose long legs d are extended forward beyond the said draw-head B. On said legs d is placed a link or ring, E, which, when pushed to the ends of said legs d, causes the jaws b to close on the coupling-pin and hold it in vertical position in or over aperture c. The extremities of these legs d are bent outward, as shown at f, to prevent the disengagement of said ring E.

Centrally from the front of the opposite car A' is projected a rectangularly-bent rod or horn F, that is designed to enter between the

legs d of the clamp D and move the ring E to cause the jaws b to open and release the coupling-pin G they have grasped.

When it is desired to couple the cars the coupling-pin G of the car A is held up by the clamp D, as shown in Fig. 2, and the coupling-link H is held ready for coupling on the coupling-pin G' of the car A'. Then, as the cars approach to each other, the free end of the link H enters the draw-head B, and the horn F, entering between the legs d of the clamp D, pushes the ring E rearward and pushes apart the said legs d, thereby causing the jaws b to open and release the coupling-pin G, which then falls of its own gravity through the link H, and thereby couples the cars. The heads of the coupling-pins G G' are bent at right angles, or made in any other convenient shape for the ready grasping and releasing of the clamp D.

This device is very simple and effective, and obviates the necessity of going between the cars for coupling them.

Having thus fully described my invention, I claim as new and desire to secure by Letters Patent—

1. An improved car-coupler, constructed substantially as herein shown and described, consisting of a pair of clamps pivoted above the draw-head, the arms of the clamps carrying a sliding ring, E, as set forth.

2. In a car-coupler, the combination of the clamp D and ring E with the draw-head B, substantially as herein shown and described, whereby the link-pin may be grasped and held, as set forth.

3. In a car-coupler, the combination, with the clamp D and sliding ring E, of the horn F, substantially as herein shown and described, whereby said clamp is released and the coupling-pin allowed to drop when the cars come together, as set forth.

JOEL REN.
